U.S. Appl. No. 29/635,426, filed Jan. 31, 2018, Pending.

Primary Examiner — T Chase Nelson(74) *Attorney, Agent, or Firm* — Quarles & Brady LLP**CLAIM**

The ornamental design for a shoe, as shown and described.

DESCRIPTION

FIG. 1 is a top, left, and front perspective view of an ornamental design for a shoe;

FIG. 2 is a left side elevational view of the shoe of FIG. 1; FIG. 3 is a top, left, and rear perspective view of the shoe of FIG. 1;

FIG. 4 is a right side elevational view of the shoe of FIG. 1; and,

FIG. 5 is a top, right, and rear perspective view of the shoe of FIG. 1.

The dash-dash-dash broken lines are included for the purpose of illustrating portions that form no part of the claimed design.

1 Claim, 5 Drawing Sheets---
